UNITED STATES PATENT OFFICE.

FREDERICK W. CHRISWELL, OF SEATTLE, WASHINGTON, ASSIGNOR TO PACIFIC CAR AND FOUNDRY COMPANY, OF SEATTLE, WASHINGTON, A CORPORATION OF WASHINGTON.

FILLER FOR LOG BUNKS.

Application filed January 27, 1925. Serial No. 5,056.

To all whom it may concern:

Be it known that I, FREDERICK W. CHRISWELL, a citizen of the United States of America, and resident of the city of Seattle, in the county of King and State of Washington, have invented certain new and useful Improvements in Fillers for Log Bunks, of which the following is a specification.

My invention relates to logging bunks and consists of a construction in which the stake-holding and controlling elements of the bunk are made as a separate construction capable of being assembled as a whole, independent of the bunk body, and inserted in or secured as a whole to the bunk body, whereby the parts of a logging bunk which are most subject to breakage may be replaced when broken without having to discard the entire bunk and all its parts.

The object of my invention is to produce a type of construction for a bunk and the essential working elements of a bunk, such that the parts which are most subject to breakage may be replaced or repaired at a cost much less than where they are built as essential elements of the bunk as a whole.

The particular constructions and combinations of parts upon which I desire to secure a patent may be seen from a study of the following specification and the accompanying drawing.

In these drawings I have shown a bunk which embodies my invention, the same having the construction which is preferred by me for the particular type of bunk. It is, however, evident that the principles of my invention may be applied to bunks of a different type of construction with as great advantage as to the type of construction illustrated.

Figure 1 is a longitudinal vertical section through the bunk and also through the frame of the fillers employed.

Figure 2 is a transverse section of the bunk body, showing the construction which has been illustrated in the other figures.

Figure 3 is an end view of the bunk with the filler in place and the stake raised.

Figure 4 is a top or plan view of a filler for one end of the bunk, the bunk body and its relative position being indicated by the broken lines.

Figure 5 is an end view of the filler frame

with the stake omitted and with the position of the side members of the bunk body indicated by broken lines.

Practical experience with logging bunks developed the fact that the breakage of any essential part of the bunk, excepting as it might be the stake or the controlling bar therefor, made it necessary to discard the entire bunk. It also has developed that where the bunk body is broken this generally occurs at one end and includes the parts thereof which are used for supporting and controlling the stakes. Such breakage, where the bunk is made as a steel casting, involves the discarding of the entire bunk.

In my present invention the bunk body is intended to be made or preferably should be made of wrought metal sections which, when subjected to heavy blows such as would break a steel casting, may give and bend but will not break. As this type of sections is of a simple character, as, for instance, of the two bulb angles and the channel 10, as shown in Figure 2, these may be straightened without having available any very especial machinery or apparatus. If, therefore, the essential operating parts may be supplied and inserted in the bunk body, repairs may be secured at a minimum loss of time, by the use of very ordinary repair facilities and at a slight expense for parts.

In my present invention the particular construction of the bunk body is not the essential feature, except in so far as the same may be adapted for the reception of the filler sections and the parts mounted thereon.

The fillers illustrated in the accompanying drawings involve the use of a frame which has two side members 20 adapted when used in connection with the bunk body illustrated, to be inserted within and closely fit between the side webs 1 of the bunk body. The filler is then secured in place by riveting or bolting.

The two side webs 20 are connected by transversely extending members which as illustrated comprise a top web 21 and cross bars 22 and 23. Such other cross connecting webs or bars as may be desired and which will not interfere with the action of the other parts may be employed.

The stake 3 employed is of a well-known

type of construction. It has two arms which are connected at substantially right angles to each other and at the end of one of these arms, is provided with trunnions 30 extending each way therefrom and adapted to engage the bunk, or, rather in the present instance, the filler, so as to be supported thereby. At the angle at which the two arms are joined the bunk is also provided with laterally projecting bosses 31, which are provided with inclined supporting surfaces 32 adapted to engage complementary supporting surfaces carried by the main frame. These are inclined so that if the whole action of the controlling bars 4 is released the tendency will be for the stake to move outwardly sufficient to carry the supporting trunnions 31 beyond the end of the web 24 which forms a part of the filler frame. This web 24 projects inward from each of the side webs 20. They are, however, separated a sufficient distance to permit the main body of the stake 3 to drop freely between them.

The lateral position of the stake lengthwise of the bunk and of the filler is controlled by a bar 4 which extends to the opposite end of the bunk and at that point is provided with laterally offset boss or bosses 40. The filler frame has a web 22 provided with a notch 24, the same being so positioned with reference to the bar 4 and the lugs or offsets 40 thereof, that the main body of the bar may drop down into the notch 24, while the boss 40 will engage the side surface of the bar 22 and thus prevent endwise movement of the bar 4 in the direction which will permit movement of the stake 3 which is connected therewith. If the end of the bar 4 be raised so as to free it from engagement with a bar 22, the stake 3 will then be free to move outwardly so as to drop down into the log-freeing position or that which is shown at the right hand end of Figure 1.

It frequently happens that the load placed upon the bunk does not bear against the stake at the time it is desired to dump the load in such a way as to exert an outward push upon this stake. Under these conditions it may happen that the stake will not move outwardly when the opposite end of the controlling bar 4 has been released. To insure positive drop of the stake when the opposite end of the bar 4 is released, I provide the following means. Located a short distance above the locked position of the controlling bar 4 is a web 25 which has an inclined surface so positioned as to be engaged by the end of the bar 4 when the latter is raised and when so engaged further upward movement of the bar 4, as would naturally occur, will cause an endwise movement of the bar sufficient to start the stake 3 and insure that it will drop. This web 25 is secured to or formed as an integral part of the filler frame.

To insure that the controlling bar 4 will not be released by jarring movement incident to the movement of the car, a logging block 5 is employed, this being mounted upon a pivot bar 50 which extends to the outside of the bunk and has secured thereto a handle 51. These parts are mounted upon the pivot bar 50 so that gravity holds them depending therefrom or in the locking position. When these are thrown upward or into the position shown at the left-hand end in Figure 1, the bar 4 may be raised into releasing position.

As a stop to control the outward movement of the stake 3 a block 6 is shown as being dropped into openings provided in the body of the filler frame. The block is provided with a laterally offset portion 60 adapted to engage the flange 27 and prevent further dropping. It is thus held in the channel formed by the flange 27 and the top plate 21, so as to engage the trunnions at the side of the stake and limit its outward movement.

If at any time any portion of the filler, which latter contains the working parts of the bunk, become broken, it is a comparatively short job, and one which may be accomplished by the use of few tools, to remove said filler and insert another. Also, if when this breakage occurs any part of the bunk body becomes bent, these, by being of simple type, may also be straightened and restored by the use of simple and few tools.

My invention is not limited to a filler having the exact construction herein described and shown in the accompanying drawings. My invention, broadly considered, includes the idea of providing a separate insertible filler which may be renewed if any part thereof is broken. It also includes the idea of so constructing the parts most subject to breakage that they may be incorporated in such an insertible assembly.

What I claim as my invention is:

1. A stake holding frame for use in log bunks comprising side walls and connecting tie members, flanges extending horizontally inward from the side walls and lengthwise of the frame to form stake pivot guides, said flanges being notched outwardly of the stake-pivoting point for the reception of a pivot stop, and a notched transverse member adapted for holding the stake controlling bar.

2. A filler for insertion in a log bunk comprising a frame adapted for insertion as a complete assembly in a bunk body and having therein a pivot support for a stake and means for locking engagement with the controlling bar for the stake at the opposite end of the bunk.

3. A filler for a log bunk comprising a frame independent of and adapted to be secured to the end of a bunk body, said frame having means for supporting a stake

and a transverse web notched to releasably secure the controlling bar for the stake at the opposite end of the bunk.

4. A logging bunk comprising a frame having means for lockingly engaging the controlling bar for the stake at the opposite end of the bunk and a deflecting member positioned to be engaged by said controlling bar when released to thereby give said bar

10 an endwise movement.

5. Locking means for logging bunks, in combination with a bunk body and stake supporting means thereon, comprising a holding bar, a transverse web provided with 15 a bar-receiving notch, the bunk body, above and outwardly of this notch, having a deflecting surface positioned to engage the end of said holding bar when raised from said notch to thereby give said bar a limited 20 endwise movement.

6. As an article of manufacture, a filler frame for log bunks provided with means for securing it upon the end of a bunk frame and having incorporated therewith means 25 for supporting a stake pivot to permit a limited movement of said pivot lengthwise of the said frame and a supporting member adapted to engage the stake to hold it raised and to be disengaged from the stake by an 30 endwise movement of the stake.

7. As an article of manufacture, a filler frame for log bunks provided with means for securing it upon the end of a bunk frame and having incorporated therewith means

for supporting a stake pivot to permit a 35 limited movement of said pivot lengthwise of the said frame and a supporting member adapted to engage the stake to hold it raised and to be disengaged from the stake by an endwise movement of the stake, said frame 40 also having means for engaging and holding the controller bar for the stake at the opposite end of the bunk to prevent its movement lengthwise of the bunk.

8. As an article of manufacture, a stake 45 holding frame for log bunks provided with means for holding a stake in raised position and to permit its dropping down when desired, and means for securing said frame to the end of a bunk body. 50

9. As an article of manufacture, a frame provided with means for assembling thereon a stake and for controlling said stake to hold it in raised position and for dropping the stake, and means whereby such frame 55 with its attached parts may be secured to and removed from a bunk as an assembled whole.

10. A logging bunk comprising a beam built from rolled sections and having a stake 60 receiving gap formed by cutting short its horizontal member at each end, a filler frame inserted in each end of the beam and stakes mounted upon said filler frames and adapted when raised to extend through said gaps. 65

Signed at Seattle, King County, Washington, this 10th day of January, 1925.

FREDERICK W. CHRISWELL.
